UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

CONNECTER SLEEVE.

Application filed August 3, 1923. Serial No. 579,357.

To all whom it may concern:

Be it known that I, CHARLES E. GODLEY, a citizen of the United States, and residing at Detroit, in the county of Wayne and State 5 of Michigan, have invented a new and Improved Connecter Sleeve, of which the following is a specification.

My invention relates to means for mounting completely assembled electric connecters 10 on supporting walls, such as the sides of automobile head lamps, and particularly for supporting such a connecter so that it will operatively extend through the supporting wall.

Connecters for such use commonly comprise cylindrical shells having spring-pressed plungers mounted within and insulated from the shells, each plunger being electrically connected at its inner ends to a 15 wire leading to the lamp of the head light. Owing to the confined space between the casing or body of the lamp and the reflector mounted within this lamp body, it is desirable that such a connecter should pass 20 obliquely through the wall of the casing or body so as to bring the wire within the lamp closer to this casing. At its outer end, each such connecter is commonly equipped for interlocking with a detachable wire carrying 25 plug. Since the plug when attached extends axially of the shell of the connecter, it is likewise desirable to have the axis of the shell oblique to the wall through which it extends, thereby avoiding an unsightly 30 projecting of the plug and wire from the lamp.

Furthermore, since the assembling of electric connecters involves the delicate manipulating of rather small parts, it is desirable 35 that this should be done before any part of the connecter proper is attached to the lamp.

My present invention aims to meet all of these requirements by providing a cheaply manufactured mounting which can readily 40 be attached to the lamp during the regular course of manufacture of the lamp, by providing this mounting so that it will be oblique with respect to the wall through 45 which it extends, and by providing it with 50 parts which can easily be bent into inter-

locking relation to an inserted (completely assembled) connecter to hold the latter in position. Moreover, it aims to provide a sleeve or connecter holder which can easily be manufactured from a single sheet metal 55 stamping.

In the illustrated embodiment, my invention consists in a sheet metal blank rolled into a cylindrical sleeve which is adapted to receive a connecter and provided with ears 60 at its ends so that the sleeve may be secured to a lamp body or other structure and with lips which may be turned in to secure the connecter within the sleeve. It further consists of a sleeve which is so formed that 65 the ears will be in the same central plane of the sleeve but diagonally opposite each other so that the sleeve may be secured in an opening in the wall of a lamp body or other structure with its ends on opposite 70 sides of said wall. It also consists of the details of construction illustrated in the accompanying drawing and particularly pointed out in the claims:

In the drawing, Fig. 1 is a plan of a blank 75 for this improved connecter sleeve. Fig. 2 is an elevation of the sleeve in position in the wall of a lamp body on a central plane of the lamp body. Fig. 3 is an elevation thereof at right angles to Fig. 2. Fig. 4 is 80 a section in the line 4-4 of Fig. 3. Fig. 5 is an elevation of a connecter. Similar reference letters refer to like parts throughout the several views.

Many of the reflecting lamps used as 85 headlights and search lights for motor vehicles and search lights for launches are provided with reflectors separate from the bodies. A sleeve or other holder is mounted in the wall of the body and into it extends a connecter at one end of the wire leading to the lamp bulb in the reflector. This connecter in the holder has an end open to the outside 90 of the lamp to receive a removable connecter plug at the end of a conductor extending 95 from a current source. The connecter is usually permanently secured in the wall of the lamp body.

In the present case the connecter sleeve 11 is formed of a blank 1 shown in Fig. 1, 100

having perforated ears 2 and 3 and a small lip 4. This blank is bent to cylindrical form and the ears 2 and 3 are then attached to the wall 5 of the lamp body by means of 5 rivets 6.

- The connector forms no part of the present invention but consists of a tubular body 7 having a perforated end 8 through which the conductor 9 extends. A spring 10 within 10 in the connector presses out against the washer 12 of insulating material and this washer presses against the contact 13 at the end of the conductor. The body 7 has bayonet slots 14 to receive the usual retaining pins on the cylindrical plug which is usually attached to the end of the supply conductor, which plug is inserted in the connector body 7. This body 7 is also formed with a notch 15 to receive the tongue 16 15 formed on the sleeve to prevent movement of the connector in one direction, movement in the other direction being prevented by the lip 4 when bent down as shown in Fig. 2.
- 20 The connector sleeve is preferably attached to the lamp body while that is being produced by punching an elongated opening and a pair of rivet holes at opposite ends thereof, inserting the connector sleeve with 25 both of its ears bearing against the same face of the wall, and then riveting the ears to the wall. Later on, as the lamp is being wired, the connector is inserted and the lip 4 is bent down against it and I prefer to se- 30 cure the ears 2 and 3 to the same side of the wall 5 of the body. The size of the sleeve

11 will depend upon the size of the connector 7 to be mounted therein.

I claim:

1. A cylindrical connector sleeve having 40 perforated ears at its ends and inwardly turned lips and a connector within the sleeve secured in position by said lips.

2. A cylindrical connector sleeve having 45 perforated ears at its ends in a central longitudinal plane whereby it may be secured in position, said ears being diagonally opposite each other, said sleeve also having an inwardly turned lip at one end and a second lip adjacent the other end, and a connector mounted within the sleeve and secured in position by the lips. 50

3. In combination, a cylindrical connector sleeve and a tubular body mounted therein, the connector sleeve being formed with 55 tongues at its ends projecting inwardly to secure the tubular body in position, the sleeve being also formed with a perforated ear at each end, said ears being diagonally opposite each other and adapted to lie flat 60 against a cup-shaped body to support the sleeve thereon with its open ends on opposite sides of the support.

4. A mounting sleeve as per claim 1, having a pair of lips formed therefrom and 65 adapted to be bent respectively into engagement with forward and rearward portions of the inserted connector, one of the lips being adapted to prevent the connector from rotating.

CHARLES E. GODLEY.
